(57) **CLAIM**

The ornamental design for mermaid bottle, as shown and described.

DESCRIPTION

FIG. 1 is a front perspective view of a mermaid bottle, showing our new design.

FIG. 2 is a rear perspective view thereof;

FIG. 3 is a front elevational view thereof;

FIG. 4 is a rear elevational view thereof;

FIG. 5 is a right side elevational view thereof; and,

FIG. 6 is a left side elevational view thereof.

The broken lines in the drawings depict portions of the mermaid bottle that form no part of the claimed design.
